UNITED STATES PATENT OFFICE

161,212

LEATHER TABLE TOP OR SIMILAR ARTICLE

Louis Scalera, Newark, N. J.

Application December 9, 1949, Serial No. 6,526

Term of patent 3½ years

(Cl. D33—14)

To all whom it may concern:

Be it known that I, Louis Scalera, a citizen of the United States, residing in the city of Newark, in the county of Essex and State of New Jersey, have invented a new, original, and ornamental Design for a Leather Table Top or Similar Article, of which the following is a specification, reference being had to the accompanying drawing, forming a part hereof:

The figure is a top view of a leather table top showing my new design. The table top is of conventional thickness.

I claim:

The ornamental design for a leather table top or similar article, as shown and described.

LOUIS SCALERA.
